FRANZ VINCENT, OF BRIDGEPORT, CONNECTICUT.

POCKETKNIFE.

1,411,649.

Specification of Letters Patent.

Patented Apr. 4, 1922.

Application filed October 14, 1920. Serial No. 416,972.

To all whom it may concern:

Be it known that I, FRANZ VINCENT, a citizen of the United States, residing at Bridgeport, county of Fairfield, State of Connecticut, have invented an Improvement in Pocketknives, of which the following is a specification.

This invention relates to pocket knives having a blade sliding in and out of an enclosing handle casing.

One object is to provide a sliding blade with a head fitting closely the interior of the casing so as to be held firmly in operative position.

Another object is to supply a shield for the knife aperture for preventing the admission of foreign matter.

Still another object is to provide an improved operative and locking mechanism for controlling the position of the blade in retracted and extended position.

A further object is to utilize a stamped out one piece seamless casing whose interior surface shall be completely finished in the stamping process so as to provide a proper bearing surface for parts sliding therein and which shall have its interior corners clean and well formed.

Other objects will become evident in connection with the description of the accompanying drawing forming a part of this specification, in which:

Fig. 1 is a reduced perspective view of the knife with the blade in retracted position;

Fig. 2, a reduced perspective view with the blade extended;

Fig. 3, a side view with the casing sectioned showing the parts in position;

Fig. 4, a similar side view with the blade retracted;

Fig. 5, a similar edgewise view showing the rod in position at one side of the blade and the shield in position;

Fig. 6, a perspective view, in detail, of the upper end of the rod and related parts disassembled; and

Fig. 7 is a perspective view of the shield.

The casing has a body portion 10 formed of a single piece of stamped seamless metal, made by well known processes, slotted at 11, of elliptical cross section and suitably roughened on its exterior. For covering the slot a shield 12 is placed at one side of the slot.

The shield comprises a semi-elliptical part 13, which is the shield proper, a spring blade portion 14 and a flange or offset 15 which

bears against the flattened side of the casing. An elongated slot 16 encloses the reduced end 17 of the rod 18 which is seated and turns or oscillates in the hole 19 to one side 60 of the slot 11. The reduced end of the rod has a length equal to the thickness of the casing and the shield proper 13 and a shoulder 20 rests upon the shield proper so as to hold it in place and at the same time permit 65 sliding of the shield proper beneath it as will be described.

The rod 18 extends lengthwise of the casing 10 at one side of its center and is provided near its other end with a collar 21 at 70 one side of a recessed bearing member 22. The recessed bearing member is entered in the open end of the casing and makes a close fit with it. It is held by reason of a driving fit or is sweated in place.

The recessed bearing member has a transverse or stop portion 23 and an engaging sleeve portion 24 which extends around the edge of the stop portion except where it is cut away at 25 to make room for the button 26 which sets over the end of the rod so as to have a sliding fit thereon as later described in detail. Between the button and the stop portion 23 a spiral spring 31 is placed.

The sleeve 24 extends beyond the open end of the body 10 of the casing and a cap 32 is sweated to the sleeve to close the end of the casing. The cap has a rectangular slot 27 centrally located through which the corresponding rectangular end 29 of the button passes with a sliding fit. In order to locate the head 29 in the central slot 27 it is offset on the body of the button 26 and a rim 30 is formed on the button to provide a suitable 95 stop surface on the button.

Referring to Figure 6 the button is seen to have a central cylindrical recess 35 with a short pin 36 which is entered in the groove 37 forming in effect a cylindrical cam surface. As the recess is of the same diameter as the rod 18 it is plain that the pin and slot will serve to turn the rod 18 when, as in Figure 4, for instance, the button is depressed against the spring 31. As the button is held 105 from rotation by the recess 25 in the bearing member 22, the rod will rotate in its bearings about a half turn in the direction of the arrow upon depression of the button and in the reverse direction when the button 110 is released and the spring returns it to its first position.

The rotation of the rod serves to move the three lugs 38, 39 and 40 on the rod 18 which are integral with the rod 18. Lugs 38 and 39 are carefully faced on opposite surfaces so as to form latches as later explained while lug 40 serves to displace the shield proper 13 by pressing upon the spring blade 14.

When the button 29 is depressed the rotation of the rod is such as to force the lug 40 against the blade 14 of the shield and then slide the shield proper away from the slot 11 and uncover it so the blade may pass through the slot. Upon the reverse rotation of the rod the lug 40 will be moved away from the blade 14 and by action of the spring blade the shield proper will be moved back to cover the slot after the blade has returned to the interior of the casing. When the knife blade is extended it holds the shield away from the slot.

The knife blade 41 of usual form has a shank 42 drilled so as to receive a pin 43 which fastens it to a head 44. In order to maintain the head rigidly in the casing but at the same time to permit sliding therein the cross section of the head is practically that of the interior surface of the casing and sufficient length is given the head so as to provide enough bearing surface.

A slot 45 centrally located is made in this head to receive the shank 42 of the knife. The depth of this slot is such as to receive the rod 18 within it at one side of the shank and its width is made such as to clear the flange 15 of the shield and at the same time to be guided and steadied by the edges of the flange.

Lug 38 is shown passing over the edge of slot 45 and upon the end surface of the head 44 when the blade is retracted and in Figure 3 lug 39 is shown as bearing upon the other end surface of the head at the edge of the slot 45 and these lugs thus serve to retain the blade in latched position in retracted or extended positions.

Pressure on the end 29 of the button will rotate the lug 38 out of latching position and move the shield from the slot 11. When the button is depressed and held the head 44 is unlatched and this release will allow the knife blade 41 to pass through the uncovered slot 11 into the position shown in Figure 3. When the button end 29 is released the spring returns the button to normal position and the pin 36 in slot 37 returns the shaft 18 to starting position and consequently the lug 39 passes over the inner end surface of the head 44 and latches. The knife is now ready for use.

In order to retract the blade the button is again pressed and the head 44 unlatched, the blade dropped back into the casing and latched in retracted position and the shield allowed to return to its place over the slot.

It should be noted that the rotation of the

shaft 18 at this time moves the lug 40 against the spring blade 14 and presses it back so that the blade can freely pass the shield proper 13.

Having thus described my invention; I claim:

1. In a knife, a seamless casing body, a blade, a head fastened thereto, a latching surface on each end of said head, a rod, lugs on said rod, means to oscillate said rod and place the lugs in latching position upon the end surfaces of the head.

2. In a knife, a casing, a rod mounted for oscillatory movement, latching lugs thereon, a spring surrounding one end, a spiral cam surface on said rod, a button mounted on one end of said rod bearing on the spring and turning on said rod, and a pin on said button engaging the cam surface.

3. In a knife, a casing having a slot at one end thereof, a shield therefor having a shield portion, an oscillatory rod, a bearing therefor adjacent said slot, said shield proper having an opening through which said rod passes to said bearing, means on said rod preventing displacement of the shield while permitting the sliding of the shield proper, a flexible blade on said shield sliding it in one direction, and means on the rod sliding the shield in another direction upon oscillation of the rod.

4. In a knife, a casing, a knife blade, a head therefor sliding in said casing, an oscillatory rod for latching and releasing the head and blade, a bearing for the rod in one end of the casing, a second bearing near the other end of the casing, a recessed bearing member carrying the second bearing and fastened in the casing, a button recess in the bearing member, a button sliding in said recess and having an end extending without the casing, a spring between the button and the bearing member, a cam surface on said rod, a pin on said button moving thereon, said button moving in said recess when its extending end is pressed and turning said rod, and said spring moving the button and turning the rod in reverse direction when the extending end of the button is released.

5. In a knife, a casing, a rod therein, bearings therefor in the casing, actuating means for the rod causing movement in one direction and the reverse, a plurality of latching lugs on said rod and a shield moving lug on said rod, said shield moving lug having a position co-related to the position of the latching lugs.

6. In a knife, a casing body of seamless material, a recessed bearing member therein securely attached thereto, a cap secured to said bearing member, a rod in said casing, a bearing at one end of the casing therefor preventing longitudinal movement of the rod, a collar near the other end of the rod preventing longitudinal movement of the

rod, a bearing in the recessed bearing member adjacent the collar, said rod by reason of its attachment within the casing serving to stiffen the casing and prevent distortion thereof.

5. 7. In a knife, a casing, a knife blade, a head fastened to the knife blade and having a lateral central slot, said casing having a

slot for the passage of the knife blade, a shield for the slot, and a flange on said 10 shield fitting within the slot in the head and alining the head when the knife blade is in extended position.

In testimony whereof I affix my signature.

FRANZ VINCENT.
